JOHN C. SHAMBOW, OF WOONSOCKET, RHODE ISLAND, ASSIGNOR TO SHAMBOW SHUTTLE COMPANY, OF WOONSOCKET, RHODE ISLAND, A COPARTNERSHIP.

SHUTTLE-EYE.

1,324,933.

Specification of Letters Patent.

Patented Dec. 16, 1919.

Application filed April 14, 1919. Serial No. 289,790.

To all whom it may concern:

Be it known that I, JOHN C. SHAMBOW, a citizen of the United States, residing at Woonsocket, in the county of Providence and State of Rhode Island, have invented a new and useful Improvement in Shuttle-Eyes, of which the following is a specification.

This invention relates to certain new and useful improvements in a shuttle eye and it has for its primary object to provide an improved friction device for placing a drag on the thread as it leaves the eye.

A further aim of the invention resides in the mounting of the eye in the shuttle whereby the latter is reinforced against splitting which is frequently the situation in the shuttles now in use and resulting from the weakening of the shuttle body upon insertion of the eye.

The invention further resides in the features of construction and the arrangements and combinations of parts hereinafter described and claimed, reference being had to the accompanying drawings wherein—

Figure 1 is a top plan view of a shuttle equipped with the improved eye construction.

Fig. 2 is a view of the complete shuttle eye.

Fig. 3 is a fragmentary view of the shuttle showing the eye in vertical section, and

Fig. 4 is a transverse section through the shuttle, depicting the eye in elevation.

Proceeding in accordance with the present invention, the shuttle body 1 is formed with the threading slit 2 for directing the thread from the bobbin cavity 3 to the eye constituting the subject matter of the improvements.

To this end, the shuttle is formed with a vertical bore 4 and a horizontal bore 5 intersecting the lower end of the bore 4 and having its adjacent end wall formed with a reduced thread opening 6 to which the threading slit leads. Adhesively secured within the vertical bore 4 is a tubular fiber bushing or cylinder 7 having a transverse opening 8 registering with the horizontal bore 5 and communicating with the threading slit 2 through a lateral passage 9.

Threaded in one end of the bore 5 is a nut or plug 10 carrying an inwardly projecting eye base 11 which supports a pair of guides 12, the foremost guide having a downwardly inclined entrance slot 13 and the companion

guide having a horizontal entrance slot 14, both entrance slots communicating with the threading slit.

In assembling the parts of the eye, the fiber bushing is first disposed in the vertical bore and glued therein with its transverse opening 8 in registry with the horizontal bore 4 into which the metal eye is now inserted by threading the plug 10 in the outer end. As the plug is advanced into the bore, 65 the eye part, comprising the base 11 and guides 12, is also advanced into and through the transverse opening 8 of the fiber bushing until such advancing movement is limited by abutment with the end wall of said horizontal bore, when the eye passages of the guides will coincide with the thread opening 6. In this position the guides are partly disposed within the side walls of the bushing whereby the latter is firmly held in position by 75 means additional to the glue securing.

Disposed between the guides 12 and within the bore of the fiber bushing is a frictional device in the nature of a glass, or other vitreous, shoe 15 which has a seat in its upper face for one end of a coiled tension spring 16, the latter having its opposite end engaged in the hollow underside of an adjusting nut 17 that is threaded in the upper end of the fiber bushing. The tension of the 80 spring and, consequently the drag of the shoe on the underpassing thread, is varied and adjusted by turning the nut 17 as by inserting a tool in the opening 18 which extends through the nut and thereby permits 85 inspection of the interior of the eye.

In threading the eye, the thread will pass beneath the glass shoe and into the guides 12. As the thread is drawn through the shuttle eye the friction of the shoe will control the same in an efficient manner and prevent it from unthreading. Furthermore, it frequently happens in the use of shuttles, that the wood portion immediately above the eye, being weakened by reason of the insertion of the eye, will split and thus render the shuttle useless. The provision of the fiber bushing overcomes this defect and trouble since the eye is supported and reinforced or bound thereby.

Having thus described my invention, what I claim as new and desire to secure by Letters Patent is—

1. A shuttle having a horizontal bore and an intersecting vertical bore, a fiber bushing 110

disposed within the vertical bore and formed with a transverse opening registering with the horizontal bore, a metal eye secured within the horizontal bore and extending 5 through the transverse opening of the bushing serving to lock the latter in the vertical bore, and a glass friction device accessible through the bushing and coöperating with the eye to place a drag on the thread as it

10 leaves the eye.

2. A shuttle formed with a threading slit leading to a horizontal bore which intersects a vertical bore also in the shuttle, a bushing disposed within the vertical bore and formed 15 with a transverse opening communicating through a lateral slot with the threading slit, a metal eye comprising a plug threaded in the horizontal bore and having a base extending through the opening of the bushing, said base having a pair of upstanding guides on opposite sides of the bore of the bushing and within the side walls thereof, said guides having lateral slots communicating with the threading slit, a vitreous shoe 20 interposed between the guides on the base to drag on the underpassing thread, a spring seating on the shoe, and a tensioning nut threaded in the bushing and bearing on the spring.

25 3. A shuttle having a threading slit leading to an eye passage intersecting a vertical bore, a bushing secured within the bore and formed with a transverse opening in registry with the eye passage, an eye arranged in the latter and extending through the opening 30

of the bushing to secure the latter in position, and a friction device arranged within the bushing and coacting with the eye to control the thread as it passes out of the eye.

4. A removable shuttle eye comprising a 40 base having two spaced upstanding and registering thread guides, each with an entrance slot angularly related to the slot of the companion guide.

5. A shuttle eye comprising a threaded 45 plug adapted to be inserted in an eye passage of a shuttle, an eccentrically disposed support extending from the plug in parallel relation to its axes, and spaced upstanding thread guides carried by the support and 50 formed with registering thread passages having entrance slots angularly related to each other.

6. A shuttle eye having a lateral opening through which the thread is accessible, a 55 friction device operable through the opening to place a drag on the thread, a removable tubular body through which the eye extends transversely and which houses the friction device within the lateral opening of the eye, 60 and means within the body for varying the tension on the friction device.

In testimony whereof I have signed my name to this specification in the presence of two subscribing witnesses.

JOHN C. SHAMBOW.
